UNITED STATES PATENT OFFICE.

WINTHROP K. HOWE, OF ROCHESTER, NEW YORK, ASSIGNOR TO GENERAL RAILWAY SIGNAL COMPANY, OF ROCHESTER, NEW YORK, A CORPORATION OF NEW YORK.

UNIVERSAL RELAY.

Application filed July 19, 1920. Serial No. 397,327.

This invention relates to alternating current relays used in railway signaling systems.

The objects of the invention are to improve and simplify the construction of alternating current relays, increase the efficiency and reliability of their performance, and to provide an arrangement and organization of parts which can be readily converted or adapted to suit the various working conditions and requirements ordinarily found in practice. Various other objects and advantages of the improved relay will be pointed out as the description progresses.

In describing the invention in detail, reference will be made to the accompanying drawings, in which like reference characters designate corresponding parts in the several views, and in which

Figure 1 is a front view of one side of the relay, with part of the casing broken away;

Fig. 2 is a front view of another side of the relay, with the lower part of the device in vertical section;

Fig. 3 is a horizontal section through the relay taken substantially on the line 3—3 in Fig. 1;

Fig. 4 is a horizontal section through the stator and rotor, taken substantially on the line 4—4 in Fig. 2;

Fig. 5 is a vertical section through the stator taken substantially on the line 5—5 in Fig. 4;

Figs. 6 to 11 are detail views of parts of the device;

Figs. 12 to 14 are perspective views, diagrammatic in their nature, and having some parts broken away or omitted, which show different arrangements of the contacts and operating mechanism; and

Fig. 15 is a detail section of an insulated stud for the contact fingers.

The parts of the relay are supported and enclosed in a boxlike casing which is made up of a skeleton framework, comprising a base 1, corner posts 2, and upper cross members 3; a top plate or panel P of slate, porcelain or similar insulating material, which is fastened to said framework by screws 4; and glass side walls 5 fastened to the framework by bezel rings 6 provided with suitable gaskets.

The relay is constructed so that the parts may be assembled in different ways to make

up the various combinations or organizations of parts ordinarily required in practice in railway signaling systems. The construction illustrated provides for three-position or two-position operation, with either a direct-connected rotor or a pinion-and-sector connection, and with various contact arrangements. In the three-position operation, the rotor, which in relays of this type constitutes the power element, may be driven in either direction, depending upon the way in which its operation windings are energized; and consequently, some contacts may be closed when the relay is energized in one way, and others when it is energized in another way, these different groups of contacts being commonly termed the normal and reverse contacts. In the two-position operation, the rotor is driven in one direction and only one group of contacts are closed when the relay is energized. In both the three-position and two-position operation, the contacts of the relay have de-energized positions to which they are biased by suitable counterweighting means and tend to assume when current is cut off from the relay.

The parts of the relay are conveniently grouped and described separately as follows:—The stator and rotor construction of the operating motor; the contacts or circuit controlling devices; the counterweighting means; and the relay movement connecting the rotor to the contacts.

The operating motor comprises a multi-polar stator a shell-type rotor, and a fixed core within the rotor. These parts are carried by a detachable bottom plate 7 fastened by screws 8 to the base 1 of the main framework of the relay. This bottom plate 7 has an integral hollow core support 9 on which the laminæ 10 of the core are pressed. The stator is made up of a circular yoke 11, and a plurality of pole pieces 12. This stator yoke 11 consists of a stacking of laminæ in the form of split rings having their ends slightly separated, the joints of the several rings being staggered, as shown in Figs. 1 and 4. Angle brackets 13 are riveted to the ends of this stator yoke 11 and are connected by clamp screws 14 (see Fig. 1) so that the yoke may be contracted. Each of the pole pieces 12 consists of a stacking of T-shaped laminæ riveted together and having a butt joint with the yoke 11.

The whole stator, including the yoke 11 and the pole pieces 12, is supported by the walls of a rotor casing which comprises upper and lower octagonal shells 15 and 16 (see Fig. 5) 5 of brass or other suitable non-magnetic material, and a cover 17 fastened to the upper shell 15 by tap bolts (see Fig. 2). The lower shell 16 is fastened to the bottom plate 7 by screws having their heads countersunk in re- 10 cesses in said bottom plate. The stator is disposed between the shells 15 and 16, with suitable interposed gaskets, and said shells are clamped together by a number of long screws 18 surrounded by suitable bushings. These 15 screws 18 pass between the tips of the pole pieces 12, these tips being slightly recessed to receive said screws and bushings (see Fig. 4). The coils 19 for the stator are formwound, and are put in place before the pole pieces 12 20 and the stator yoke 11 are assembled. By tightening the screws 14, the yoke 11 may be contracted to form a tight joint with the pole pieces 12 and hold all the parts rigidly together. The alternate coils 19 are connected 25 in series, as shown in Fig. 3, to form a two-phase winding, comprising a local winding and a track or line winding.

The rotor comprises a hub 20 and a shell 21, the shell being made of brass, aluminum or similar light and electrically conducting material. The hub 20 is connected to a rotor shaft 22 by a friction clutch and lost-motion device shown in detail in Fig. 6. This device comprises a driving member 23 loose on the 30 shaft 22 and having two radial arms which engage lugs 20^a integral with the hub 20. On each side of this member 23 is a washer 24 having an integral tongue fitting into the slot or keyway 25 in the rotor shaft 22, and between said member 23 and each washer 24 is a friction disc 26, these parts being pressed together by a spring 27. The inner washer 24 bears against a shoulder on the shaft 22, and the rotor hub 20 may turn freely on said 35 shaft except as its movement is limited by the engagement of the lugs 20^a with the arms of member 23 and friction between member 23, washers 24, and the friction disks 26.

When the stator windings are energized 40 with alternating current having the proper phase displacement, the rotor is caused to rotate in one direction or the other, depending upon the phase relation of the currents in said windings, in much the same way as the well known induction motor operates. Assuming 45 that the rotor turns in the counter-clockwise direction as viewed in Fig. 6, the lugs 20^a engage the arms of member 23 and drive the shaft 22 and actuate the circuit controlling 50 elements of the relay. During this operation the movement of the parts is comparatively quick, and the friction clutch is employed so that the rotor may, if necessary, continue its movement and overrun slightly in opposition 55 to the friction of the clutch, when the circuit

controlling elements stop, thereby avoiding shock and jar to the mechanism.

Upon deenergization of the relay, which in practice is usually done by cutting off the supply of alternating current to one of the 70 stator windings while maintaining it on the other or local windings, the parts of the relay, including the shaft 22 and the rotor 21, are returned to their neutral or biased position, by the counter-weighting means hereinafter 75 described. This return movement drives the rotor 21 and its shaft 22 backward, that is, in the clockwise direction in the instance assumed; and during this backward movement the rotor acquires considerable momentum on 80 account of its speed and weight. After the circuit controlling elements of the relay come to a stop in the deenergized position, the rotor may continue its movement for part of a revolution, and one of the stator windings being 85 energized, the rotor is gradually braked and brought to rest by the eddy currents induced in it by this winding, and also by the friction between the hub 20 and shaft 22. Thus, the momentum of the rotor is absorbed and does 90 not tend to rotate the shaft 22 beyond its biased position and produce the objectionable "bobbing" of the contacts which often occurs in practice when the rotor is directly connected to its shaft and the circuit controlling 95 elements.

The rotor shaft 22 is arranged vertically and is supported in upper and lower jewel bearings. To avoid cracking or injury of the jewel in the lower bearing on account of shock or jar, the shaft 22 is spring supported, as best shown in Fig. 9. The lower end of the shaft 22 is bored and counterbored to three diameters. A ring jewel 28 fits in the largest 100 diameter bore (the edges of the shaft being spun over to hold this jewel in place): a cap jewel 29 fits loosely in the next size bore; and a small spring 30 is located in the smallest bore. A flanged stud 31 is pressed into a hole 105 in the bottom plate 7 and has an integral polished bearing pin 31^a, with a rounded end, which passes through the ring jewel 28 and bears against the cap jewel 29. The spring 30 absorbs the shocks and jars sometimes 110 occurring in service or shipment, and thus protects the cap jewel 29 from cracking or other injury.

The upper bearing for the rotor shaft 22 comprises a flanged bearing pin 32 set into the upper end of said shaft (see Fig. 8) and a ring jewel 33 fitted into a recess in the end of a screw 34, the edges of said screw being spun over to hold the jewel in place. In the direct-connected type of relay (shown in Figs. 1 and 2), the screw 34, with a suitable 115 jam nut, is mounted in a cross member 35 fastened to the upper ends of two standards 36 which are formed integral with the cover 17 for the rotor casing. In the pinion-and-sector type (shown in Figs. 7 and 10), this 120

screw 34 is threaded into the cover 17^a itself, the cover in this instance being shaped differently to accommodate the pinion-and-sector movement, as hereinafter explained.

5 The contacts or circuit controlling parts of the relay include a number of fingers F attached to a rocking carrier bar C, and a number of front and back contacts cooperating with said fingers. The carrier bar C, 10 preferably made of aluminum for lightness, extends crosswise of the relay and is provided with upturned ends which are pivotally supported on trunnion pins 37 in the lower ends of brackets 38, a bushing for 15 each trunnion pin being preferably fastened in the upturned ends of said carrier bar (see Fig. 2). The brackets 38 are fastened to the underside of the top plate P with screws, and are split and provided with clamping screws 20 for holding the trunnion pins 37 in place (see Fig. 1).

The contact fingers F are fastened to the carrier bar C by insulated studs 39 (shown in section in Fig. 15) which comprise two 25 screw-threaded members 40—40^a imbedded in a block 41 of molded insulation, said members being provided with suitable grooves preventing them from turning or pulling out of the block 41. One of the members 40 is 30 screwed into a hole in the carrier bar C, and the other member extends through a hole (preferably elongated for adjustment purposes) in the contact finger F, a nut provided with suitable locking means serving 35 to clamp said finger in place.

The body of each contact finger F is made of a relatively stiff bar of steel 42, white-nickel or otherwise suitably protected against rust, or of brass, or other similar 40 conducting material. This bar 42 is bent as shown in Fig. 1 to form a retainer or stop for a spring 43 of phosphor-bronze or similar material which is fastened at one end by eyelet rivets to the middle of said bar 42. The 45 contact piece for each finger F is made up of a carbon button 44 seated in a sheet metal cup 45, as shown in Fig. 11, which has its edges spun into a circumferential groove in said button and which is fastened by rivets 50 to the spring 43.

Several constructions and arrangements of contact fingers, suitable for different conditions, have been illustrated. In one arrangement, Fig. 1, a carrier bar C wide enough to 55 take four rows of studs 39 is used, and to each pair of studs is fastened a front and a back contact finger, the back contact finger being offset downward, as shown in Fig. 1. If desired, either a front or back contact finger 60 alone may be fastened to each pair of the studs 39. The carrier bar C in the particular construction illustrated is long enough for four sets of fingers (see Fig. 2), so that 65 this arrangement of contacts provides a contact capacity of eight electrically dependent

normal and reverse contacts for three-position operation, or eight dependent front and back contacts for two-position operation.

In another arrangement of contacts shown in Fig. 14, a narrower carrier bar C, only 70 wide enough to take two rows of studs 39, is used; and for electrically dependent normal and reverse contacts, a double length or through finger F^b is fastened to the two studs. For electrically independent normal or 75 reverse contacts, an L-shaped finger F^b is employed and is fastened to the carrier bar C by two studs 39 disposed lengthwise of said bar. This construction provides a lighter carrier bar and affords a contact capacity sufficient 80 for the majority of applications of the relay for railway signaling.

The stationary front and back contacts, with which the contact fingers F cooperate, are adjustably fastened to binding posts B 85 supported by the top plate P. The construction of these binding posts is substantially the same, and a description of one will suffice for all. Referring to Fig. 10, the binding post B is formed with a square head 46 which 90 fits in a groove in a metal clip 47 which sets over a ridge on the top plate P. The upper end of the post B is threaded to receive the usual nuts 48 for attaching wires. When the post B supports a front contact, as shown 95 in Fig. 10, it is made long enough to extend a short distance below the top plate P.

The front contact comprises a stem 49 which is threaded in an axial bore in the post B; and a jam nut 50, with the usual split 100 lock washer, is threaded on said stem 49 and engages a spacing sleeve 51, hexagonal in cross section, which is seated in a hexagonal recess in the under face of the top plate P. This sleeve 51 is long enough so that the nut 105 50 bears against it, rather than the end of the post B. The nut 50 not only clamps the post B in the top plate P, but also locks the stem 49 of the front contact in its different adjusted positions. Near the lower end of the 110 stem 49 is a hexagonal head 52 for facilitating adjustment of said stem; and below said head the stem terminates in a circular button having undercut edges, over which is fitted a wafer 53 of silver or similar non-corrosive 115 and highly conductive material, said wafer being held in place by having its edges spun over said button.

The back contact comprises a stem 49^a, constructed the same as stem 49 but shorter, 120 which is threaded in a horizontal flange of a bracket 54, a jam nut being provided to lock this stem 49^a in its adjusted positions. The upper end of the bracket 54 has a horizontal flange fitting in a groove in the under face of the top plate P; and this flange is fastened to a binding post B by a screw and lock washer.

The flexible connections to the several contact fingers F, commonly termed the pigtail 130

connections, comprise a clip 55 clamped under the nuts holding the finger on its insulated studs 39; a pigtail 56 consisting of a flexible copper strip, a braided band, or the like, which is riveted and soldered, or otherwise fastened, to said clip 55; and an angle bracket 57 attached to a binding post B in the same way as the bracket 54, the other end of the pigtail 56 being secured to this bracket 57 by a screw, or in any other suitable way.

An additional middle row of binding posts is provided, as shown in Fig. 1, to accommodate additional pigtail connections, when required, as for example, when there are more than two electrically independent fingers under the two regular pigtail or "heel" posts. Additional pairs of binding posts B¹ and B² are fastened to the top plate P, and to each of these posts is fastened a bracket 58 having a terminal clip 59 for connecting the lead wires (not shown) for the local and track windings of the stator. The contact carrier C is preferably grounded to the frame of the relay by a flexible connection 60 of braided copper or the like, as shown in Fig. 2, so as to protect the contacts from lighting.

The relay movement, constituting the operative connection between the rotor 21 and the contact carrier C, comprises a hanger H fastened to the underside of the carrier bar C by two capstan-head screws 61, said hanger having a ridge between said screws bearing against the carrier bar C, so that the hanger may be adjusted back and forth with respect to said bar. In one construction, (Figs. 1 and 13), this hanger H is shaped like an inverted U; in another form (Fig. 14) like an inverted Y; and in still another form (Fig. 12) which is designed for two-position operation, the hanger has only one arm. The lower ends of the arms of the hanger H are bifurcated and carry revoluble rollers 62. These rollers 62 engage opposite sides of a larger roller 63. In the direct-connected type, Figs. 1, 8, 12 and 14, this large roller 63 is journaled on an eccentric axis between two jaws integral with the rotor shaft 22. In the pinion-and-sector type, Figs. 7 and 13, the roller 63 is carried by an auxiliary operating shaft 64 extending parallel with the rotor shaft 22 at one side thereof, said auxiliary shaft being mounted on jewel bearings, the same as the rotor shaft, supported by the cross member 35 and the cover 17. (See Fig. 7.) The rotor shaft 22 drives the auxiliary shaft 64 through a pinion 65 and a sector 66 fixed to said shafts respectively.

If desired, adjustable screws 67, with enlarged heads and suitable lock nuts, may be threaded into the standards 36, as shown in Fig. 14, so as to provide stops against which the rollers 62 may strike and thus limit the movement of the carrier bar C. In two-position operation, one of these screws 67 may be advanced far enough to form a back stop for

the carrier bar C in the deenergized condition of the relay. In the construction shown in Fig. 12, the back stop is provided by a member 68 integral with the cross member 35, and the front stop by a similar member (not shown) also integral with the cross member 35 and a fixed or adjustable pin therein for engaging the roller 63.

Counterweighting.—Two arrangements of counterweights for three-position operation are illustrated, one acting directly on the rotor shaft 22 (Figs. 1 and 2), or the auxiliary shaft 64 (Fig. 13), and the other directly on the carrier bar C (Fig. 14). In the first construction, a horizontal counterweight shaft 70 is mounted on pointed trunnion pins 71 fastened in lugs 72 integral with the cross member 35, said trunnion pins being held in said lugs by small transverse screws gripping said pins. This shaft 70 has a sector-shaped arm 73 integral therewith, in which are a plurality of holes; and a number of weights 74 are fastened to said arm 73 in different positions by a bolt passing through one of said holes. Also carried by the shaft 70 are two pairs of arms 75, and between each pair of these arms is pivotally mounted a small roller 76. The rollers 76 bear against rollers 77 carried by pairs of arms 78 extending radially from the rotor shaft 22, or the auxiliary shaft 64, as the case may be. The parts are shown in Figs. 1, 2 and 13 in the deenergized or biased position. If the rotor shaft 22, or the auxiliary shaft 64, is rotated by the rotor 21 in either direction, the counterweight shaft 70 is rocked in the same direction by the action of the rollers 76—77, so as to raise the weights 74. The counter torque is adjusted by changing the number of the weights 74, or by fastening them in different holes in the arms 73, the latter adjustment varying the lever arm of said weights with respect to the axis of the shaft 70.

In the other arrangement of counterweights shown in Fig. 14, a lifting bar 80 is fastened to the carrier bar C, and this lifting bar has adjustable stop screws 81, with suitable lock nuts, screwed in it near each end. Each of these screws 81 engages a weighted arm 82 which is pivotally supported at one end in a stirrup 83 fastened to the top plate P. These weighted arms 82 normally rest upon horizontal flanges of stop brackets 84 which are fastened to the top plate P. The weighted arms are provided with a hole and a bolt by means of which additional weights 85 may be attached. As the carrier bar C is rocked in one direction or the other, one or the other of the weighted arms 82 is raised, thereby creating a bias tending to return the carrier bar C to its neutral or deenergized position. In this construction the counterweighting is varied by changing the number and thickness of the additional weights 85.

For two-position operation, a single counterweight for returning the carrier bar C and the other moving parts of the relay to the neutral or deenergized position may be employed, as shown in Fig. 12. Such a counter-weight comprises a plate 86 fastened by screws to the carrier bar C, and having a depending arm at one side of the pivotal axis of said carried bar, this arm being provided with a bolt for supporting any selected number of weights 87. This counterweight bracket 86 may be fastened to the carrier bar C so as to project from either side thereof.

In some contact arrangements for three-position operation, there are more contact fingers projected from one side of the carrier bar C, and in such cases, in order to balance said carrier bar, a bracket similar to the bracket 86 is used and the appropriate 20 weights added to obtain the desired balance.

In connection with the adjustment and maintenance of a relay of the type described, it is often desirable to be able to ascertain accurately the extent of movement of the rotor shaft; and for this purpose a pointer 90 is fastened by rivets or other suitable means to the motor shaft 22 (see Figs. 2 and 3) so as to move over a scale 91 fastened to the cover 17 of the rotor casing. This scale 91 may be 30 graduated in degrees or any other desired units. The pointer 90 may also be used in connection with the oscillating shaft 34 (Figs. 7 and 13).

Among the advantageous features of the improved relay construction embodying this invention, it will be observed that the rectangular shape of the relay affords a decided space economy when it is required to place several of the relays together on a shelf or 40 in a cabinet. All of the wiring connections are made to binding posts on the top of the relay, and this enables the several relays to be placed close together.

All of the moving parts, with the exception 45 of the rotor, are readily inspected through the glass side walls. The rotor itself is enclosed in a protecting casing, so that dirt or other foreign substances cannot accumulate or drop into the air gap around the rotor and 50 prevent its proper operation. Furthermore, since the rotor is arranged to turn on a vertical axis, there is practically no chance for dirt to pile up in the air gap and bind the rotor. Some clearance is of course necessary 55 around the rotor shaft where it passes through the cover plate 17; and this space is preferably made smaller than the air gap around the rotor, so that any particles of dirt or the like able to get into the rotor casing 60 around the shaft will not be large enough to stick the rotor. The same protection is provided for the pinion and sector (see Fig. 7) so that there is no opportunity for foreign matter to lodge in the teeth or otherwise obstruct 65 free movement of the parts. Likewise, any

wear occurring in the pivot bearings or the rotor shaft 22 will not tend, on account of this vertical arrangement of the shaft, to change the air gap and perhaps result in the rubbing of the rotor on the pole pieces of the 70 stator. The vertical arrangement of the rotor also facilitates the making of an organization of parts which will occupy a limited space, while having sufficient clearances and the desired accessibility and visibility. The point- 75 to-jewel vertical bearing support for the rotor reduces the friction to a minimum, and also does not require any lubrication. This feature is of importance because it is desirable in relays of this type to obviate the need for lu- 80 brication, since the device will in practice be inspected at irregular intervals and may not receive the necessary amount of lubrication, or perhaps may receive too much. Further, a jewel bearing of this type will not 85 rust or be affected by the fumes or gases to which relays in railway systems are often subjected. As previously explained, the spring suspension for the rotor obviates injury of the jewels by careless handling. 90

The stator construction provides wide pole pieces while retaining the advantages of form wound coils. The larger surface area of the stator pole pieces increases the amount of flux acting on the rotor shell. Referring to Fig. 95 4, it will be noted that in the particular construction illustrated, flux acts upon practically the entire circumference of the rotor. The increase in leakage flux resulting from this construction, as distinctive from one employing narrow pole pieces, is not as a rule 100 objectionable in railway signaling relays, and in fact, on certain track circuits this leakage flux is an advantage because it assists in obtaining the desired phase displacement in the 105 local and track windings. In this connection it should be noted that the multi-polar stator and rotor construction embodying this invention permits larger air gaps and greater clearances without lowering the efficient performance of the relay. The coils of the stator winding are outside of the rotor casing or compartment, so that if the compound (with which the coils are impregnated in accordance with well known practice) should soften 110 and flow or drip, it cannot get into the rotor casing and interfere with the movement of the rotor, but will drop down on the bottom plate 7 where it will do no harm.

Special provisions are made to facilitate the 115 assembly, inspection and repair of the relay. By taking out the screws 4 and disconnecting the necessary wires, the top plate P, together with the entire contact organization, can be taken off without disturbing the operating 120 mechanism. Likewise, by taking out the screws 8 the bottom plate 7 and associated parts, can be readily detached as a unit. This construction also permits the insertion 125 of any type of movement in the same case. 130

The various parts of these units may also be readily taken apart, as will be obvious.

The circuit controlling parts of the relay are organized so that they may be readily 5 changed and adapted for the different requirements found in practice. The use of a contact carrier with fingers projecting in opposite directions from both sides, gives a larger contact capacity in the same space and 10 also facilitates making up some of the peculiar contact combinations required. The front and back contacts 49 are adjustable up and down with respect to their cooperating contact fingers. This adjustment, when once 15 made, is permanent and cannot be accidentally or carelessly changed from the outside of the relay, as for instance, by tightening the nuts on the binding posts. The whole contact carrier C may be adjusted by the screws 20 61 with respect to the rotor shaft and the operating mechanism associated therewith.

The operating connections between the rotor and the contact carrier C is obtained by the cooperation of rollers merely having rolling contact with each other, rather than by a link or similar connection, so that friction is greatly reduced and there is less chance for derangement or binding of the parts.

Other detail features of the construction 30 which add to the accessibility of the parts, decrease the cost of manufacture and assembling, and improve the performance of the device and its adaptability to the varying and exacting conditions found in practice, will be 35 evident without detail explanation.

What I claim as new and desire to secure by Letters Patent of the United States, is:—

1. A relay comprising a box like casing having glass side walls and a top plate of insulating material removably fastened thereto, a pivotally supported rocking carrier bar supported by the top plate, contact fingers attached to the carrier bar and insulated therefrom, fixed contacts cooperating with said fingers also supported by the top plate, a bottom plate removably fastened to said casing, electro-magnetic means in the lower part of the casing supported wholly by the bottom plate for operating said carrier bar, and 45 means including members having operably operating contact with one another for operatively connecting said rocking carrier and electro-magnetic means, whereby either the rocking carrier bar or the electro-magnetic 50 means may be separately removed from the casing.

2. A relay comprising a box like casing having glass side walls and a top plate of insulating material, circuit controlling means 60 in the upper part of the casing supported wholly by the top plate and removable therewith and including a pivotally supported carrier bar supporting contact fingers insulated therefrom, an electro-magnetic motor in the 65 lower part of the casing for actuating said cir-

cuit controlling means, said motor being wholly carried by the detachable bottom plate, and means including members having separably operating contact with one another for operatively connecting the motor and the 70 circuit controlling means, whereby either the top plate with the circuit controlling means or the bottom plate with the motor may be separately removed.

3. A relay, comprising a box like casing 75 having glass side walls, a top plate of insulating material removably fastened to said casing, circuit controlling means in the upper part of said casing supported wholly by the top plate, a bottom plate removably fastened to said casing, a motor in the lower part of the casing wholly supported by said bottom plate and including a rotor supported on a vertical axis, and quick detachable means operatively connecting said circuit controlling means to 85 the motor comprising parts merely bearing against each other.

4. A relay for railway signaling purposes comprising, a shaft, an electro-responsive device for driving said shaft, and means for 90 biasing said shaft to a predetermined position including cooperating rollers rolling against each other.

5. In a relay for railway signaling purposes, the combination of a shaft, electro-responsive means for turning said shaft, a roller eccentrically supported by said shaft, and pivotally supported circuit controlling means 95 having rollers secured thereto and engaging opposite sides of said first mentioned roller. 100

6. A relay for railway signaling purposes comprising, a shaft, electro-responsive means for operating said shaft, circuit controlling means, and means for operatively connecting said shaft to said circuit controlling means 105 including a roller eccentrically supported from said shaft, said shaft and roller being constructed so that the axis of the shaft passes through said roller.

7. In a relay for railway signalling purposes, the combination of a casing consisting of a tubular transparent portion having an end wall removably secured to each end thereof, a circuit controller wholly supported by one end wall including a member for operating the same, and an electro-responsive device wholly supported by the other end wall and including an operating member, said circuit controller and electro-responsive device being so secured to their respective end walls 115 and having their cooperating operating members so constructed that operation of said electro-responsive device causes its operating member to engage the operating member of said circuit controller so as to cause operation of said circuit controller, whereby replacement of either of said end walls after having been removed re-establishes the operating connection between said controller and device. 120 130

8. In a relay for railway signalling purposes, the combination of a casing having its top wall and its bottom wall removably secured to the rest of the casing, a circuit controller wholly supported by the top wall and including an operable member, and an electro-responsive device wholly supported by the bottom wall and including an operating member, said circuit controller and electro-responsive device being so secured to their respective walls and having their cooperating operable and operating member so constructed that operation of said electro-responsive device causes said operating member to engage said operable member and in turn cause operation of said circuit controller, whereby replacement of either of said walls after having been removed re-establishes the operating connection between said controller and device by reason of engagement of said members.

9. A contact construction for relays comprising, a panel of insulating material having a hole therein, a raised, plane topped ridge of non-circular configuration around said hole, a contact post in said hole having an enlargement of non-circular configuration, a separate member receiving said post and engaging the outside face of said ridge and the outside face of said enlargement, and a nut on the lower end of said post for preventing said post being lifted and in turn preventing it being turned.

10. In a relay, a rocking contact carrier bar, spring contact fingers supported by said bar but insulated therefrom, stationary contacts adapted to be engaged by said spring contact fingers, operating means for said bar including a hanger adjustably connected thereto said hanger having a fulcrum engaging said bar, and adjustable anchoring means on opposite sides of said fulcrum for forcing said fulcrum against said bar.

11. In a relay, a rocking contact carrier bar tiltable about an axis, a roller supported by said bar so that its pivot is eccentric to the axis of the bar, a shaft disposed at an angle to the axis of said bar and having a roller located eccentrically with respect to the axis of said shaft, said last mentioned roller cooperating with the roller supported by said bar for operating the bar by said shaft, whereby one member is operated by another member through the medium of two rollers having their axis disposed at an angle to each other.

12. In a relay, a contact carrier bar mounted to rock on a horizontal axis, rollers supported from said bar to turn on a horizontal axis, a vertically arranged operating shaft, a roller carried by the shaft and cooperating with said first mentioned rollers.

13. In a relay, a rocking contact carrier bar, spaced rollers supported from said bar, an operating shaft, and a roller carried by said shaft on an eccentric axis and located between

and cooperating with said first mentioned rollers, whereby movement of said shaft in either direction about its axis operates said bar through the medium of one of said rollers and said second mentioned roller.

70

14. In a relay, pivotally supported circuit controlling means, an operating shaft angularly disposed with the axis of said circuit controlling means, and means operatively connecting said shaft to the circuit controlling means and comprising cooperating revolute rollers having their axes disposed at an angle to each other.

75

15. In a relay, a top plate, a rocking carrier bar, insulated contact fingers supported by said bar, and a counterweight pivotally supported directly from the top plate and acting on one side of the axis of said bar to bias said bar to its initial position.

80

16. In a relay, a top plate, a rocking contact carrier bar, movable counterweights pivotally supported from the top plate, and means operated by said bar for raising one or the other of the counterweights as the bar is rocked in opposite directions from a middle position.

85

17. In a relay, a rocking contact carrier bar, a lifting bar fastened to said carrier bar and projecting in opposite directions therefrom, adjustable stops in the ends of said lifting bar and movable counterweights engaged by said stops.

90

18. In a relay, the combination with a top plate of insulating material, of a rocking carrier bar supported by said top plate, vertically movable weighted arms supported from the top plate on opposite sides of said bar, stops for limiting the downward movement of the weighted arms, and a lifting bar fastened to the carrier bar and adapted to lift said weighted arms alternately as the carrier bar is rocked in opposite directions from a middle position.

100

19. In a relay for railway signalling purposes, the combination of a casing having its top wall and its bottom wall removably secured to the rest of the casing, a circuit controller wholly supported by the top wall including a contact carrier bar which may be rocked about a horizontal axis and a hanger depending therefrom, and an electro-responsive device for operating said circuit controller supported wholly by the bottom wall and including a vertically disposed shaft having a member eccentrically disposed with respect thereto, said circuit controller and electro-responsive device being so secured to their respective walls and being so constructed that operation of said electro-responsive device operates said circuit controller by causing said member to strike against said hanger, whereby the replacement of either said circuit controller or said electro-responsive device on the casing after having been removed automatically re-establishes the op-

erative engaging connection between said member and said hanger.

20. A contact construction for relays comprising, in combination with a panel of insulated material having a non-circular raised ridge on its upper surface surrounding a hole in said panel, a post having a similar non-circular head contained in said hole with its head against said ridge, a clip between said ridge and head cooperating with the outside face of said head and the outside face of said ridge to prevent turning of the post in the hole, screw threaded means on the lower side of said panel for holding said post on said clip and said clip about said ridge, for preventing removal of said post from the top, and a stem carrying a contact piece at its lower end adjustably supported by said post.

21. In a relay for railway signalling purposes, the combination of a shaft, electro-responsive means for turning said shaft, a roller eccentrically supported by said shaft, and pivotally supported circuit controlling means having rollers secured thereto engaging opposite sides of said first mentioned roller, the parts being so proportioned that the roller supported by said shaft lies in the axis of said shaft.

22. A relay for railway signalling purposes comprising, a shaft, an electro-responsive device for driving said shaft, and means for biasing said shaft to a predetermined position including a roller having its axis disposed eccentrically with respect to said shaft, the parts being so proportioned that the axis of said shaft passes through said roller.

23. A relay comprising, an open frame work, a top plate of insulating material detachably secured to said frame work, a bot-

tom plate, circuit controlling means including 40 a plurality of contact fingers and insulated contacts supported wholly by the top plate and removable therewith, and an electro-responsive device supported by the bottom plate, said circuit controlling means and said 45 electro-responsive device being operatively connected by engaging rollers supported by the respective devices, the parts being so proportioned that the roller supported by said shaft lies in the axis of said shaft. 50

24. A relay for railway signaling purposes comprising, a vertically disposed shaft, an electro-responsive device for driving said shaft, circuit controlling means pivotally supported about a horizontal axis, a roller eccentrically supported by said shaft, and another roller supported by said circuit controlling means, said rollers being in contact with each other and forming an operative connection between said shaft and said means. 55

25. A contact construction for relays comprising, a panel of insulating material having a hole therein, a raised, plane topped, ridge of non-circular configuration around said hole, a contact post in said hole having 60 an enlargement of non-circular configuration, a separate member receiving said post and having non-circular grooves in its lower and upper faces for lockingly engaging the outside face of said ridge and the outside face of said enlargement, and a nut on the lower end of said post for preventing said post being lifted and in turn preventing it from being turned. 70

In testimony whereof I have affixed my 75 signature,

WINTHROP K. HOWE.
